US0D1024053S

(12) **United States Design Patent** (10) Patent No.: **US D1,024,053 S**
(45) Date of Patent: ** Apr. 23, 2024

(54) **LAPTOP COMPUTER**

(71) Applicant: **Lenovo (Beijing) Limited**, Beijing (CN)

(72) Inventor: **Zhaochun Pang**, Beijing (CN)

(73) Assignee: **Lenovo (Beijing) Limited**, Beijing (CN)

(**) Term: **15 Years**

(21) Appl. No.: **35/517,377**

(22) Filed: **Mar. 7, 2023**

(80) **Hague Agreement Data**

Int. Filing Date: **Mar. 7, 2023**

Int. Reg. No.: **DM/229022**

Int. Reg. Date: **Mar. 7, 2023**

Int. Reg. Pub. Date: **Jun. 2, 2023**

(30) **Foreign Application Priority Data**

Sep. 30, 2022 (CN) 202230662702.1

(51) **LOC (14) Cl.** **14-02**

(52) **U.S. Cl.**

USPC **D14/315**; D14/439

(58) **Field of Classification Search**

USPC D14/315-328, 353-355, 432, 439-441, D14/444-446; D8/403; D21/324, 515

CPC G06F 1/1616; G06F 1/1601; G06F 1/1613

See application file for complete search history.
